UNITED STATES PATENT OFFICE

158,378

HOSIERY CASE OR SIMILAR ARTICLE

Frances Handlen, New York, N. Y.

Application June 29, 1949, Serial No. 3,610

Term of patent 3½ years

(Cl. D58—12.6)

To all whom it may concern:

Be it known that I, Frances Handlen, a citizen of the United States of America, residing in New York, county of New York, and State of New York, have invented a new, original, and ornamental Design for a Hosiery Case or Similar Article, of which the following is a specification, reference being had to the accompanying drawing, forming part thereof.

Fig. 2 is a front perspective view thereof, showing the case in open position; and

Fig. 3 is a rear perspective view.

I claim:

The ornamental design for a hosiery case or similar article, substantially as shown.

FRANCES HANDLEN.
